ELECTRICAL IGNITION SYSTEM FOR INTERNAL-COMBUSTION ENGINES.

1,083,285.

Specification of Letters Patent.

Patented Jan. 6, 1914.

Application filed December 6, 1912. Serial No. 735,180.

To all whom it may concern:

Be it known that I, FRANZ KRATZ, a subject of the Emperor of Germany, residing at Stuttgart, Germany, have invented certain

5 new and useful Improvements in Electrical Ignition Systems for Internal-Combustion Engines; and I do hereby declare the following to be a full, clear, and exact description of the invention, such as will enable 10 others skilled in the art to which it appertains to make and use the same.

The present invention relates to electrical ignition systems for internal combustion engines, and more particularly to a system in 15 which the apparatus for ignition during running is supplemented by such apparatus for starting the engine from rest when combustible mixture is present in a cylinder that its operation is independent of the position 20 of rest of the mechanical interrupter. For this purpose it has heretofore been proposed to use a battery and an electromagnetic interrupter having a vibratory armature connected in electrical series with a mechanical 25 interrupter driven by the engine, in combination with a manually operated switch for completing at will the circuit including the electromagnetic interrupter and the mechanical interrupter. Furthermore, it has 30 been proposed to render this prior system operative to start the engine also from that position of rest in which the mechanical interrupter has an unfavorable position for this purpose by providing an auxiliary 35 switch for closing the circuit of the electromagnetic interrupter independently of the mechanical interrupter. In this latter arrangement, it is intended that the auxiliary switch should be released immediately after 40 the engine has started, so that thereafter the mechanical interrupter may control the period of ignition and bring about the ignition of the combustible mixture at the retarded period to which the apparatus 45 would be adjusted for starting. However, if this switch is held in its operative position after the engine has started, continual spark- 50 ing occurs throughout the entire interval in which a spark plug is connected to the ignition apparatus by the distributor, so that in the usual equipments, where the distributor contacts are sufficiently extended to provide for the extreme range of adjustment of the period of ignition, premature ignition

occurs, resulting in back fire and perhaps in 55 the reversal of the engine.

In accordance with the present invention the difficulty due to premature ignition is avoided by arranging the path for completing the circuit of the electromagnetic interrupter independently of the mechanical interrupter in such manner as to include in a closed circuit the winding of the electromagnetic interrupter and a source of current, so that whenever this circuit is established, the 65 vibratory armature is attracted to a position to interrupt the electrical connection to the mechanical interrupter. In this way single 70 sparking voltages are generated in the winding of the electromagnetic interrupter when the independent path is established and interrupted, while, after the engine has started, the mechanical interrupter is effective to control the period of connection, only when 75 this independent path is interrupted. Therefore, in accordance with my invention, if the engine has started and the independent path is maintained closed, the ignition is interrupted, and the engine may stop, but 80 back-fire and reversal of the engine is avoided. However, it is intended that the independent path should be permanently interrupted soon after the engine starts so that the mechanical interrupter may thereafter 85 control the period of ignition and cause the engine to speed up to its normal speed without danger of back-fire and reversal. Certain modifications of this broad idea are disclosed herein, whereby sparking voltages 90 adapted to produce powerful sparks at the spark plugs are generated in the winding of the electromagnetic interrupter by the supplementary starting apparatus, and whereby the apparatus disclosed has practical advantages in commercial application. However, 95 it is to be understood that the idea embodied herein may be attained by various other arrangements and by the use of other kinds of apparatus, so that I limit myself only to the features within the broad interpretation of the appended claims.

In the accompanying drawings, illustrating the preferred embodiment of my invention, Figure 1 is a diagram of the circuits for a four-cylinder internal combustion engine, as an example; and Fig. 2 represents 105 diagrammatically the apparatus for a single cylinder engine, as an example, and shows

particularly the preferred arrangement of the electromagnetic interrupter and its associated parts.

In Fig. 1, the battery 1 is electrically connected to the primary winding of the electromagnetic interrupter 2 by way of the switch 13, while the other terminal of the battery is electrically connected to one contact of the mechanical interrupter 6, which 10 is driven from the engine in the well known way. The other contact of the mechanical interrupter is connected to the vibratory armature of the electromagnetic interrupter through the make and break contacts 3, 4. 15 The contacts of the mechanical interrupter 6 are shunted by the condenser 7^a, and the contacts 3, 4 are shunted by the condenser 7^b, for the purpose of suppressing the sparks thereat. One terminal of the secondary 20 winding of the electromagnetic interrupter 2 is grounded, as shown, and the other terminal thereof is connected to the rotatable brush of the distributor 8, which is driven from the engine in the well known way. 25 The distributor contacts are connected to the individual spark plugs 9 mounted in and grounded to the separate cylinders of the engines in the usual manner. The manually operated switch 11 is arranged to short circuit 30 the path through the mechanical interrupter and to establish and interrupt at will the closed circuit, including the battery 1 and the primary winding of the electromagnetic interrupter 2 by being connected on 35 one side to a terminal of the primary winding and on the other side to a terminal of the battery as shown. The electrical resistance 12 is included in the short circuiting path for the purpose of decreasing the flow 40 of current from the battery through the low resistance primary winding of the electromagnetic interrupter when the switch 11 is closed.

Fig. 2 shows the same arrangement as in 45 Fig. 1, except that it is intended for a single cylinder internal combustion engine having a single spark plug 9, no distributor being required. The iron core of the electromagnetic interrupter 2 carries the primary and 50 secondary windings, and also carries the resistance winding 12. The vibratory armature of the electromagnetic interrupter is fastened at one end to a stationary conducting support, which also carries a blade 55 spring 5 of metal, provided at its other end with one of the contacts of the manually operated switch 11. The contact 4, co-operating with the contact 3 near the free end of the vibratory armature, passes freely 60 through an opening in the blade spring 5 and is held stationary in the frame of the apparatus as indicated.

The operation of the arrangement is as 65 follows:—If the co-operating contacts of the mechanical interrupter 6 are at rest in

their closed position, then when it is desired to start the engine, it is only necessary to close switch 13. A current from the battery 1 passing through the primary winding of the electromagnetic interrupter 2 causes its vibratory armature to vibrate, and thereby to rapidly interrupt and establish the electrical circuit through the co-operating contacts 3, 4 and the mechanical interrupter 6, with the result that a series of 70 sparking voltages will be generated in the secondary winding of the electromagnetic interrupter 2, and a series of sparks will be generated at that spark plug 9 of Fig. 1 which is then selected by the distributor 8, 75 or at the spark plug 9 in Fig. 2. If combustible mixture is present in the cylinder containing the spark plug in question, it will be ignited, and the engine will start. The mechanical interrupter 6 and the distributor 8 will then be rotated with the engine and the normal cycle of operations of the engine will be initiated, the mechanical interrupter 6 controlling the period of ignition 80 in accordance with the adjustment of 85 the spark adjusting mechanism. However, if in the arrangement shown in the drawings, it is desired to start the engine from that 90 position of rest in which the co-operating contacts of the mechanical interrupter 6 are 95 separated, which position may result from an improper balance of the engine parts or from other causes, closing switch 13 will not establish an electrical circuit through the mechanical interrupter and no sparking 100 voltages will be produced, although the rotatable brush will, under almost all conditions, be in engagement with one of the distributed contacts, owing to the relatively extended contacts of the distributed parts, 105 as indicated in Fig. 1. However, by the arrangement herein shown, the engine may be started under these conditions by closing the switch 11, and then opening it, or by 110 repeatedly opening and closing switch 11 as required. When this switch 11 is closed, a current limited by the resistance 12, and also by the resistance of the primary winding of the electromagnetic interrupter 2, 115 will flow through the circuit established by the independent path containing the switch 11, thereby charging the condensers 7^a and 7^b in series. A voltage will then be induced in the secondary winding of the electromagnetic interrupter 2, but its value may not be 120 sufficiently high to produce a satisfactory ignition spark at the spark plug. Now, when the switch 11 is opened to interrupt the circuit, the current rapidly decreases to zero, especially in view of the discharge 125 from the condensers 7^a and 7^b, and a single voltage suitable for producing a powerful spark at the spark plug 9 will be induced in the secondary winding. The combustible mixture present in that cylinder will be 130

ignited, and the engine will start, although in some cases it may be desirable to repeat the operation of opening and closing the switch 11. It will be observed that during the period in which the switch 11 is closed, the co-operating contacts 3, 4, will be separated, owing to the fact that the vibratory armature will remain attracted by the magnetized core of the electromagnetic interrupter 2, so that the mechanical interrupter 6 is then rendered ineffective to control the generation of sparking voltages. However, it is intended that as soon as the engine has started, the switch 11 should be opened, so that the mechanical interrupter may thereafter become effective to produce sparking voltages at the ignition periods predetermined by the adjustment of the adjusting mechanism usually provided for this purpose. If at any time during the starting or the running of the engine, the switch 11 should be closed, nothing more serious than stopping the engine would result, the danger of premature ignition, back-firing, or reversal of the engine being obviated by the arrangement set forth, while the engine would continue its operation with its ignition under control of the mechanical interrupter as soon as the switch was released.

By winding the resistance 12 on the electromagnetic interrupter, above, below or alongside of the primary winding, or in a single layer on the secondary winding, as indicated at 12 in Fig. 2, or by winding the resistance around one of the condensers, a compact and commercial arrangement of these parts is secured.

Having thus described my invention, what I claim is:—

1. In an electrical ignition system for internal combustion engines; the combination of apparatus for ignition during running, including a source of electric current; an electromagnetic interrupter having a winding and a vibratory armature; a mechanical interrupter driven from the engine; and electrical connections therefor; of supplementary apparatus for starting the engine from rest by ignition when the mechanical interrupter has such a position as to render the ignition system for running ineffective for starting, including a switch and electrical connections for establishing and interrupting a supplementary circuit which includes the source of current and the winding of the electromagnetic interrupter; the arrangement being such that as long as the supplementary circuit is established, the mechanical interrupter is disconnected by the vibratory armature so that the operation of the mechanical interrupter is then rendered ineffective for producing sparking voltages in the winding, and such that when the supplementary circuit is interrupted, the operation of the mechanical interruption is

effective for that purpose; substantially as described.

2. In an electrical ignition system for internal combustion engines; the combination with apparatus for ignition during running, including a source of electric current; an electromagnetic interrupter having a winding and a vibratory armature; a mechanical interrupter driven from the engine; and electrical connections therefor; of supplementary apparatus arranged to start the engine from rest by ignition when the mechanical interrupter has such a position as to render the ignition apparatus for running ineffective for starting, including a switch and electric connections arranged in electrical parallel with the mechanical interrupter so as to establish and interrupt a supplementary circuit including the source of current and the winding, but excluding the vibratory armature and the mechanical interrupter; substantially as described.

3. In an electric ignition system for internal combustion engines; the combination with apparatus for ignition during running, including a source of electric current; an electromagnetic interrupter having a winding and a vibratory armature; a mechanical interrupter driven from the engine; and electrical connections therefor; of supplementary apparatus arranged to start the engine from rest by ignition when the mechanical interrupter has such a position as to render the ignition apparatus for running ineffective for starting, including a resistance, and electrical connections arranged in shunt to the vibratory armature and the mechanical interrupter so as to establish and interrupt a supplementary circuit including the source of current, the winding, and the resistance; substantially as described.

4. In an electric ignition system for internal combustion engines; the combination with apparatus for ignition during running, including a source of electric current; an electromagnetic interrupter having a winding and a vibratory armature; a mechanical interrupter driven from the engine and connected in electrical series with the vibratory armature; and electrical connections therefor; of supplementary apparatus for starting the engine from rest by ignition when the mechanical interrupter is open, including a switch, a resistance and electrical connections arranged to establish and interrupt a supplementary circuit including the source of current, the winding, and the resistance, but excluding the vibratory armature and the mechanical interrupter; substantially as described.

5. In an electric ignition system for internal combustion engines; the combination with apparatus for ignition during running, including a source of electric current; an electromagnetic interrupter having a wind-

- ing in series with a vibratory armature; a mechanical interrupter driven from the engine and electrically connected to the vibratory armature through make-and-break contacts; a condenser shunted around the make-and-break contacts; a condenser shunted around the coöperating contacts of the mechanical interrupter; and electrical connections therefor; of apparatus for starting the engine from rest by ignition when the mechanical interrupter has such a position as to render the ignition apparatus for running ineffective for starting, including a switch and electrical connections arranged to establish and interrupt a supplementary circuit including the source of current and the winding, the arrangement being such that the condensers are shunted in series across said switch; substantially as described.
6. In an electrical ignition system for internal combustion engines; the combination with apparatus for ignition during running, including a source of electric current; an electromagnetic interrupter having a winding in series with a vibratory armature; a mechanical interrupter driven from the en-
- gine and electrically connected to the vibratory armature through make-and-break contacts; a condenser shunted around the make-and-break contacts; a condenser shunted around the coöperating contacts of the mechanical interrupter; and electrical connections therefor; of apparatus for starting the engine from rest by ignition when the mechanical interrupter has such a position as to render the ignition apparatus for running ineffective for starting, including a switch, a resistance, and electrical connections arranged to establish and interrupt a supplementary circuit including the source of current, the winding of the electromagnetic interrupter and the resistance, the arrangement being such that the condensers are shunted in series across said switch; substantially as described. 45
